UNITED STATES PATENT OFFICE.

ISAAC STARER, OF NEW YORK, N. Y.

METHOD FOR LAYING OUT GARMENTS AND RULER THEREFOR.

1,360,327.

Specification of Letters Patent. Patented Nov. 30, 1920.

Application filed March 17, 1917. Serial No. 155,615.

To all whom it may concern:

Be it known that I, ISAAC STARER, of the city of New York, borough of Manhattan, in the county of New York and State of 5 New York, have invented a new and Improved Method for Laying Out Garments and Ruler Therefor, of which the following is a full, clear, and exact description.

My invention relates to an improvement 10 in devices for designing and laying out garments and patterns therefor.

In designing or laying out a pattern for a given garment of a given size, certain essential points have to be determined and 15 certain lines drawn, (such as the waist line, back neck line, etc.,) which vary according to the kind and size of garment to be laid out. These points are known to all skilled 20 designers and the exact lengths of these lines for a given size of garment have become definitely determined through experience, some of them being known directly, others depending 25 for their value upon certain numerical computations to be made by the designer.

25 In the course of my experience in cutting garments, I have discovered that certain measurements are fixed for various sizes and do not change with the change in style. Such 30 measurements are the neck width and height both in front and back, arm hole width, front and back shoulder heights (measured bottom of arm hole), scye depth and depth 35 of arm hole. I have also found that the front neck width for every size equals the arm hole width.

40 All other points vary with the change in style and the designer should, therefore, be left free to vary them without in any way interfering with the other measurements, as cross back and chest.

Moreover, hitherto, in previous systems, horizontal measurements were taken from a vertical base line. In my system, measurements are taken from back center line. This 45 makes it possible for the designer to embody in my system any desired style and measurement, as tight fit, semi and loose fit. Furthermore, according to my method, the 50 various parts of the design may be obtained independently by simple constructions, so that if an error should creep into the layout

of one of the parts, this error will not be carried over into the other parts. Thus, the front and back, for instance, may be laid out independently. This is a great advantage as very often it is desired to vary the style in one without changing the other. The improved process also provides means whereby the most important measurements 55 may be readily checked.

To carry out the process, I provide an improved form of ruler having scales so disposed that substantially none of the space on the ruler is wasted and the maximum 60 measurements obtained on one edge of the ruler. This makes it possible to use a single length ruler which may be readily carried about the person of the designer instead of the large, clumsy designer's squares such as 65 hitherto used.

70 Referring to the drawings,

Figure 1 is a plan view of one side of my ruler,

Fig. 2 is a plan view of the other side of 75 the ruler,

Fig. 3 is a view of a chart showing the manner of laying out a pattern for a lady's jacket, and shows the general method of the use of the ruler.

My improved ruler has scales for designing ladies' jackets and men's and children's coats as well as other garments such as 80 ladies' skirts and men's trousers.

The ruler as herein shown has upon one side thereof on the lower edge, Fig. 1, scales 85 A, B and C, subdivided for all sizes of garments from 14 to 48. Scale A is designed to be used for the depth of the arm hole; scale B for the scye depth and scale C for the bust line, all of them for ladies' garments.

90 On the same edge and side of the ruler will also be found scales 1, 2 and 3, respectively, subdivided for each size and which scales are used for laying out the following 95 measurements.

Scale 1 for the front neck and arm hole width; scale 2 for the cross back and cross chest, and scale 3 for the back neck. There is also scale number 9 for ladies' nine gore 100 skirts.

On the same side of the ruler, but on the

opposite edge are scale 6 and scale 7. Scale 6 is subdivided for the different sizes for the purpose of measurement of hips for skirts, and scale 7 is subdivided for the different sizes for the purpose of measuring sleeves and shoulder heights.

The stars SSS along the ruler indicate the division lines between each scale.

Fig. 2 shows the other side of the ruler.

- 10 On one edge are scales D, E and F, applicable to men's garments. Scale D is for the depth of arm hole; scale E for the scye depth, and scale F is for the bust line, each scale being subdivided for different sizes.
- 15 The same edge also has scale number 4, subdivided in sizes for measurement of trousers. Scale number 5 is applicable for the waist measure of ladies' skirts, and subdivided in various sizes. On the opposite edge of
- 20 the same side of the ruler are scales G, H and I. Scales G, H and I are for the measurement of children's garments; G being for depth of arm hole; H for the scye depth, and I for the bust line.
- 25 On the same edge are also scales 11, 13, 15, 17, 19 and 21 for the measurement of corresponding number gores of ladies' skirts.

The use and application of the ruler and its various scales will become evident from 30 the following example. Suppose it be required to make a pattern for a ladies' jacket, size 36. For this purpose, we use scales A, B and C, and scales 1, 2, 3 and 7. Referring to Fig. 3, the ruler is placed vertically on the cloth or sheet of paper from which the pattern is to be made, near or along the right edge thereof, and a line is drawn along the edge of the ruler of any convenient length. As it is desired to make 35 40 the garment of size 36, mark off on the line from the rule in each of the three section scales A, B and C, the desired size, 36, from each scale. If size 40 should be desired, mark off from the scale on the line at 40 on each scale. The lines drawn from the points A, B and C are the fundamental lines on which the garment is built. The distance A to C is called the arm-hole depth and is the equivalent of a line taken from the middle portion at the back of the neck over the shoulder to the front lower depth of the arm-hole.

The point A marked off as above is the 55 center of the neck while the point B marks the point of the scye. That is the point from which the scye depth is measured, while the point C marks the point through which the bust line passes. I have so graduated the scales A, B and C that when the points A, B and C are laid off as aforementioned, the 60 distances between the corresponding size graduations will give a certain required fundamental measurement. Thus, the distance from A to B, that is between the 36 marks on scale B to C will always be the scye depth

corresponding to the garment of size 36, while the distance from A to C, that is from the center of the neck down to the bust line is accurately the depth of the arm hole. The latter fact is empirical, that is to say, 70 I have found that measuring from the center of the neck down to the bust line gives accurately the required arm hole depth. Erect perpendiculars at the points B and C of any convenient length.

75 Now place the ruler so that the end Q of side shown on Fig. 1 is at point B of Fig. 3, and measure off from B to the second star X₂, getting point 1. Now use scale 3, making end P coincide with B, and starting at point B, measure on the perpendicular at B to the required size on scale 3, obtaining point 2. Now connect the points 1 and 2 by a line which gives the back neck.

80 From point 1 on Fig. 3, measure down on line A—B—C a suitable distance, say fifteen inches, to obtain the waist line D. This distance may vary according to the style and according to the individual, whether she is long or short waisted.

85 Erect a perpendicular at point D and measure off on this line from point D one-half inch, getting point Z. Connect points Z and 1 by a straight line. The intersection of this line Z—1 with the perpendicular at C, gives the point Y on Fig. 3.

90 We will assume that the cross back in the garment is $13\frac{1}{2}$ inches. On the perpendicular C—Y, measure off from Y on scale 95 number 2 beginning at end Q of the ruler on side shown in Fig. 1, $13\frac{1}{2}$ units (the scale is in half inches), and thus get point F (F—Y represents the cross back). Measure the distance F—Y and lay it off from B on the perpendicular erected at point B, thus 100 getting point G. Connect points G and F. On line F—G, beginning with F, measure up on the ruler, using scale A from its end Q to the first star X₁, and thus get point 105 6.

110 Now use scale 7, placing the upper edge, Fig. 1, of the ruler along the line F—G, with end P at point 6, and measure off on said scale to the required size 36 on division b of said scale 7, and get point 4. (Point 4 marks the back shoulder height). Connect 115 points 2 and 4 by a line and measure six inches on it from 2 getting point 13. (Line 2 to 13 is the length of the shoulder).

120 On the line F—G, measure off from F two and one-quarter inches to the left of F and get point 5. Draw a perpendicular to line C—F (continued) at point 5 downward in the direction of line C—D. Measure down on this perpendicular from point 5, seven and one-quarter inches and get point H. 125 This measurement varies according to size of garment. (The line 5—H is the length of under arm). Now connect points Z and H on Fig. 3. Measure from H toward Z, the distance from end Q of the ruler to the sec- 130

ond star X_2 on scale A, and get point 7. Now connect points 7 and 5 by a straight line.

On the line C—F beginning at point F, measure from end Q of the ruler, scale 1 5 to the required size (36) and get point 8. The distance between points F and 8 represents the arm hole width.

Now place the ruler so that scale number 2 lies with end Q at point 8 and measure on 10 line 8—Y, the required size (to division mark $16\frac{1}{2}$ on scale number 2), on said scale, and get point I. Now measure the distance from I to C, and measure off the same distance from B on the perpendicular at B, and 15 get point L, Fig. 3.

Now using scale A, place the ruler with end Q at point L and measure along L—B from L to the first star X_1 , thus getting point M, and holding the ruler in the same position, 20 measure off to the third star X_3 , and mark it point N, and connect points N and I.

Now place the ruler so that the edge runs through the points M and I, and beginning with point I, draw a line downward from I. 25 Using scale number 1, place the ruler with its end Q at point M, and measure M along M—B to the required size (36) on scale number 1, and get point O. Erect a perpendicular to M—B at point O, and measure off on 30 this perpendicular from end Q of the ruler to the fourth star X_4 on scale A, getting point T. Measure the distance from Y to Z and lay off this distance plus one and one-quarter inches from I in the direction of the 35 straight line through M—I getting point R, thus obtaining front length of waist. Measure the distance from I to 8, and lay off the same distance along B—N from point N, and get point 10. Connect points 8 and 10. 40 Draw a line of any convenient length through points T and 10. On this line T—10, measure down from point T a distance of eight inches for size 36, and get point 21.

45 On line H—D measure off from point H to the right of the same distance as from Z and D and get point 7 and then measure off along H—D this same distance from H to the right of H and get point 18. Connect points 5 and 18 and 5 and 7 by straight lines as shown in Fig. 3.

Using scale 7, place the ruler along line 2—4 with its end P at point 2 and measure off on scale 7 to the required size 36 in division a of this scale and get point 15. Measure the distance 2—15 and lay this off from D—Z along Z—H and get point K. Connect K—15. By drawing from K—15, the intersections of line K—15 with the Y—I 60 line, gives point 24.

Prolong Y—Z, six inches below Z, and get point E, and erect a perpendicular to the line Z—E at point E of the same length as the line D—K, thus getting point 23.

65 Measure the distance from F to 6 and lay

it off along line 2—13 from point 15 and get point 14. Connect 14 to 24 by a straight line. Measure the distance from 7 to H and lay it off along D—K from K, getting point J. Connect points 24 and J by a straight line.

Measure from R along R—H the same distance as from D to K and get point 19. Also lay off from T the same distance R—19 along T—10 getting point 16. Measure from I 75 along I—Y to four and one-half inches getting point 22. Now draw the lines 16—22, and 22—19. From 16 on the T—10 line, measure off two and one-half inches (for size 36) getting point 17. 80

Measure on the line 16—22, one and one-half inches up from 22, obtaining point 31. Connect 31 with 17. On the 22—19 line, measure down two and one-half inches from 22 getting point 30. From 19 lay off on line 85 R—H one and one-quarter inches. This gives point 20. Connect points 30 and 20.

From 23 along the line 23—E measure one inch getting point 28. Connect J—28 which should be six inches long. From H 90 measure down six inches along line 5—H prolonged and get point 25. Connect 7—25.

Prolong line I—R and measure from R six inches down along I—R and get point 29. At this point 29 erect a perpendicular to R—29 and lay off on it to the right from 29 a distance equal to the distance from E to 23, obtaining point 36. Connect points 19 and 36 by a straight line. This line 95 19—36 should be six inches long. From point 100 36 along the perpendicular 19—36 measure off a length equal to the distance between the points 19 and 20. This determines point 27. Join points 20 and 27 by the straight line 20—27, which should also be six inches 105 long and which is in the prolongation of the line 30—20. At point 27 erect a perpendicular to line 27—20. This perpendicular cuts the line 7—25 a little above 25. From the intersection of this perpendicular with 7—25 110 measure off to the right along this perpendicular a length equal to the distance from 23 to 28, getting point 26.

Measure from I two and one-half inches, (or a distance to suit along line C—I to the 115 left of I, thus getting point 34). Measure also two and one-half inches from point R along line H—R prolonged getting point 33. Draw a straight line through points 34 and 33. The intersection of this line 120 34—33 with the perpendicular 29—36 prolonged gives point 35.

Shape the back neck, arm hole and front neck as shown in Fig. 3.

Shape all curves as shown in Fig. 3. 125

When the layout is complete, the depth of arm hole may be checked by measuring the distance between points T and 8 and adding to it the length of line 1—2 the back neck line. The sum thus found should equal the 130

length A—C determined by the ruler at the beginning of the layout. The front shoulder height 8—10 may be checked by laying off point 9 on line 10—8 extending downward which is three-quarter inch down from point 8 on scale number 7. Division C and point 10 should correspond to the size indicated, as for instance size 36, in the present case.

10 Various modifications may be resorted to without departing from the spirit of the invention and the scope thereof as set forth in the following claims:

Having thus described my invention, I 15 claim as new and desire to secure by Letters Patent:

1. The method of laying out a garment consisting in drawing a vertical base line and a horizontal base line, laying off on the 20 vertical base line standard points for the neck depth and bust line, laying out on the horizontal base line a standard point for the back neck width, drawing the back center line at an angle to the vertical base line from the back neck depth point, then measuring upon the bust line from the back center line a length corresponding to the cross back 25 length of the individual person, measuring from the point so found a standard width corresponding to the arm hole width, and then obtaining other points by measurement and making the front neck width equal to the arm hole width.

2. The method of laying out a garment 35 consisting in drawing vertical and horizontal base lines, measuring the standard lengths of the back neck width, back neck depth and bust line on the two base lines, drawing the back center line at an angle to the vertical base line from the back neck depth point, measuring the cross back and arm hole width upon the bust line from the back center line, measuring the bust upon the bust line, laying out the arm hole block 40 lines parallel to the center back line, laying out the front center line parallel to the arm hole block lines, laying off on the upper horizontal base line from the front center line, front neck width equal to the arm hole 45 width, erecting a perpendicular from the inner front neck width point and laying off a standard length thereon equal to the front neck depth and drawing the front shoulder line from the point so found through the intersection of the front arm hole block line and the upper base line.

3. The method of laying out a garment 55 consisting in drawing vertical and horizontal base lines, measuring on the vertical base line extended upwardly a point for indicating arm hole depth, a back neck depth point, a bust line point and also a waist line point corresponding to the size and style, then measuring back neck width on the horizontal base line, drawing the back center line

at an angle to the vertical base line, laying off on the upper horizontal base line from the front center line, front neck width equal to the arm hole width, erecting a perpendicular from the inner front neck width point and laying off a standard length thereon equal to the front neck depth and drawing the front shoulder line from the point so found through the intersection of the front arm hole block line and the upper base line, 70 then checking the arm hole depth appearing on the layout from the arm hole depth indicated on the vertical base line.

4. The method of laying out a garment 75 consisting in drawing vertical and horizontal base lines, measuring the standard lengths of the back neck width, back neck depth and bust line point on the two base lines, drawing the back center line at an angle to the vertical base line from the back neck depth point, measuring the cross back and arm hole width upon the bust line from the back center line, measuring the bust upon the bust line, laying out the arm hole block lines parallel to the center back line, 80 laying out the front center line parallel to the arm hole block lines, measuring a standard distance upon the horizontal base line with respect to the front center line to thus determine a standard point and drawing a 85 continuation of the front center line from its intersection with the bust line, this continuation being determined from the said point of intersection and said standard point with reference to the front center line, laying off on the arm hole depth and bust line 90 a standard distance to the left of the right arm hole block line, drawing a line from this point downward parallel to the back center line to obtain the back and front junction line, drawing a waist line perpendicular to the vertical base line up to the back and front junction line, laying off the distance of the arm hole line from the back waist line upon the front center line, measuring downwardly from the intersection with the bust line and adding to this length a standard amount, connecting the point so found with the intersection of the waist line and the back and front junction line to obtain the 95 front waist line, laying off on the waist line 100 from the intersection of the back and front junction line and the waist line standard distances and laying off from the points so found angular lines and measuring on said 105 angular lines equal distances to determine the bottom line of the garment and measuring distances downward from the front waist line to correspond with the bottom line 110 so found.

5. A ruler for laying out garments having 115 scales for indicating the point for the horizontal base line, scye depth and bust line, and a scale on a line with the first mentioned scales whereby the arm hole depth may be 120 125 130

directly indicated while laying out the first two points, such arm hole depth being a check upon the arm hole depth as found in the course of laying out the garment.

5 6. A ruler for laying out garments having in combination with the scye depth, bust and back neck width scales one standard point disposed at a fixed distance from the end of the ruler for indicating the back neck depth

constituting an average depth which may be 10 used for all sizes.

Signed at New York city, in the county of New York and State of New York, this 27th day of February, 1917.

ISAAC STARER.
